(57) **CLAIM**

The ornamental design for a vegetable stretch pod, as shown and described.

DESCRIPTION

FIG. 1 is a top, front perspective view of a first embodiment of a vegetable stretch pod, showing my new design;

FIG. 2 is a bottom, front perspective view thereof;

FIG. 3 is a back elevational view thereof;

FIG. 4 is a right side elevational view thereof;

FIG. 5 is a left side elevational view thereof;

FIG. 6 is a front elevational view thereof;

FIG. 7 is a top plan view thereof;

FIG. 8 is a bottom plan view thereof;

FIG. 9 is a top, front perspective view thereof, in a condition of use;

FIG. 10 is a top, front perspective view of a second embodiment of a vegetable stretch pod, showing my new design;

FIG. 11 is a bottom, front perspective view thereof;

FIG. 12 is a back elevational view thereof;

FIG. 13 is a right side elevational view thereof;

FIG. 14 is a left side elevational view thereof;

FIG. 15 is a front elevational view thereof;

FIG. 16 is a top plan view thereof;

FIG. 17 is a bottom plan view thereof; and,

FIG. 18 is a top, front perspective view thereof, in a condition of use.

The broken lines in the drawings depict environment of the vegetable stretch pod that form no part of the claimed design.
